UNITED STATES PATENT OFFICE.

SOLOMON REPLANSKY, OF NEW YORK, N. Y.

LAMP-EXTINGUISHER.

1,211,354.

Specification of Letters Patent. Patented Jan. 2, 1917.

Application filed September 25, 1915. Serial No. 52,652.

To all whom it may concern:

Be it known that I, SOLOMON REPLANSKY, a subject of the Czar of Russia, residing at New York city, in the county of New York and State of New York, have invented new and useful Improvements in Lamp-Extinguishers, of which the following is a specification.

This invention relates to flame extinguishers for lamps and particularly to a device of this character which will be adapted for use upon oil lamps of the type designed to be carried in the hand and transported from place to place as the occasion may require, and as a principal object in view it aims to furnish a positive means for automatically adjusting itself to an active flame extinguishing position when the lamp is tilted to a dangerous angle and to cause the flame to be immediately extinguished.

As a further object in view it is desired to provide a device of the described character which will include an attaching sleeve carrying movable flame-extinguishing and smothering devices which will be successively brought into operative action on different tilted positions of the lamp.

A further object of the invention is the provision of an attaching sleeve which will be so designed that it will be capable of being quickly attached to any standard form of wick-tube and positioned thereon so as to effect a proper application of the extinguishing elements or adjustment thereof over the lighted end of the wick.

In the drawings forming a part of this specification and in which like numerals indicate similar parts throughout the several views: Figure 1 is a side view of a burner showing the application of the flame extinguisher thereto. Fig. 2 is an end view of the flame extinguisher removed from the burner.

Fig. 3 is a perspective view of the attaching sleeve. Fig. 4 is a perspective view of one of the extinguishing elements. The burner A herein illustrated is of common design used generally upon hand-lamps and only such parts thereof as are necessary to a proper understanding of the invention will be specifically mentioned herein. Rising from the gallery B, of the burner is a wick-tube C oval shaped to receive a correspondingly formed attaching sleeve 1.

The attaching sleeve 1 is formed of a single length of sheet metal and provided with relatively free terminals 2—2 whereby

the sleeve may be readily swung around the wick tube and yieldingly and frictionally secured upon said tube. This construction also furnishes a means which will permit the sleeve to be adjusted to accommodate different sizes of wick-tubes as will be observed and further, the design is such that will enable one to conveniently move the sleeve in a vertical direction upon the wick tube and in the direction of the flame end thereof for a purpose to be set forth hereinafter. The sleeve has stamped therefrom at each side, a pair of lugs 3—3, each having an aperture 4 therein.

Passing into the apertures 4 of the lugs 3—3 are pins 5 the intermediate portions of which being confined in stamped up portions of extinguishing and flame smothering devices 6. Each of these smothering devices 75 is preferably formed and stamped from sheet metal and formed to provide a relatively long flat perforated wick engaging head 7, a lower rolled terminal 8 in which a heavy body 9 is secured and designed to 80 form a weight whose office is to support the smothering element normally in a vertical position as shown in Figs. 1 and 2 where the head will be disposed beyond the flame path so that it will not obstruct the burning wick on a normal and safe position of the lamp. The roll 8 and head 7 of each element 6 are connected with each other by a flat shank 10, the width of which being less than the normal distance between the 90 lugs 3—3 and thereby permit of contraction of the sleeve manually on adjusting the same upon the wick tube. The pins 5 are free to slide in the apertures 4 to also allow for this described adjustment of the sleeve 95 upon the wick tube.

Both elements 6—6 are normally in inactive positions under the action of their weighted lower terminals and they are therefore designed for successive swinging movements on tilting the lamp from one position to an opposite position as will be nicely observed on reference to Fig. 2 of the drawing. On any abnormal and dangerous tilting of the lamp it will therefore be seen that one 100 of the smothering elements 6 will adjust itself to the change automatically and the head 7 thereof brought into immediate contact with the wick, causing the same to be 105 instantly extinguished.

What is claimed as new is:

A flame extinguisher comprising a sheet

metal sleeve, the sheet at one side of the sleeve having spaced ends, said sleeve having outstanding lugs located at its opposite sides and at points between the ends of the sleeve, there being openings provided at the edge portions of the sleeve and between the lugs at the sides thereof, flame extinguishing elements having shanks located between the lugs, pins pivotally connecting 10 the shanks with the lugs, whereby the said

shanks may swing into the said openings, and head portions carried by the extinguishing elements and adapted to enter the sleeve when the shanks enter the said openings.

In testimony whereof I affix my signature 15 in presence of two witnesses.

SOLOMON REPLANSKY.
